UNITED STATES PATENT OFFICE.

MERTON P. STEVENS, OF EAST ORANGE, NEW JERSEY.

HOLDERS FOR SHADES, REFLECTORS, AND THE LIKE.

1,073,468.

Specification of Letters Patent.

Patented Oct. 21, 1913.

Application filed January 10, 1913. Serial No. 741,147.

To all whom it may concern:

Be it known that I, MERTON P. STEVENS, a citizen of the United States, residing at East Orange, in the county of Essex and State of New Jersey, have invented certain new and useful Improvements in Holders for Shades, Reflectors, and the like, of which the following is a specification.

My invention relates to new and useful improvements in holders for shades, reflectors and the like, and broadly contemplates the provision of improved and simplified means for supporting a shade, reflector or the like, in operative position relative to an illuminating means, for example, an incandescent electric light bulb.

I do not desire to be limited to the particular type of illuminating means or to any specific form of shade, reflector or the like, in connection with which the invention may be employed, but have shown and described the same for the purposes of this application as being associated with a support for supporting an incandescent light bulb or a socket therefor, and a bell-shaped shade or reflector of well-known form having an attaching bead or flange.

The primary objects of the invention are to provide a holder for the purpose stated, which will be simple in construction, slight in appearance, convenient in operation and in which the shade or reflector engaging parts will be concealed from view.

The invention consists in the construction of parts, and the arrangement thereof in operative combination, to be more fully described hereinafter and the novelty of which will be particularly pointed out and distinctly claimed.

I have fully and clearly illustrated my invention in the accompanying drawings to be taken as a part of this specification; and wherein:

Figure 1 is a vertical central section view through an embodiment of my invention, the parts being shown in the relation assumed when holding a shade or reflector. Fig. 2 is a vertical central section view of the embodiment of my invention illustrated in Fig. 1, but with the parts in the position assumed when operated to release or receive a shade or reflector. Figs. 3, 4, 5, 6, 7 and 8 are vertical central section

views through other embodiments of the same invention, but differing from each other and from the structure shown in Figs. 1 and 2, in specific details.

Referring to the drawings by characters of reference—and more particularly to Figs. 1 and 2, 1 designates a wall or ceiling plate of any suitable construction and design, and adapted to be secured to a supporting member or surface by any desirable means. This plate 1 is formed with a central tubular projection or nipple 2, which is preferably 60 interiorly threaded as at 3. 4 designates a cylindrical coupling piece or member having a nipple-extension 5, threaded as at 6, and adapted to be screwed into the threaded bore of the nipple 2. I do not desire to be 70 limited to the exact manner of uniting said coupling-piece and the supporting plate, as I have shown the threaded connection only as being a convenient and efficient means of connecting the parts. 7 designates a source 75 of, or means for, illumination, in the present instance shown as consisting of a socket to receive the stem of an incandescent electric light bulb (not shown), said socket having a threaded nipple 8, which, when the 80 parts are assembled, is screwed into the lower threaded socket 9 at the end of the bore of the coupling-piece 4, whereby the socket is supported. Supported from the coupling-piece 4, at the end opposite to the 85 nipple 5, is a shade or reflector engaging and holding means, which preferably is made from a blank of spring metal, and consists of a center piece 10, from which radiate and depend a plurality of spring engaging-fingers 11 adapted to engage and hold a shade, reflector, or the like, in proper relation to the source of illumination. The said holding means may be secured in position by a variety of means; but I prefer to form the 95 center-piece 10 with a central aperture 12, to receive the threaded nipple 8, on the socket-piece 7, so that, when the said nipple is screwed into place in the coupling-piece 4, said holding means will be securely and rigidly clamped between the socket and the lower end of the coupling-piece. The spring-fingers 11 are of spring sheet metal, and are disposed in circular arrangement concentric with the coupling-piece 4, and each is directed outwardly in a general di-

rection longitudinally of the fixture, as at 13, for a suitable distance, where it is again directed outwardly and then inwardly to form a locking recess 14, on the inner faces 5 of said finger, to receive the bead or flange on the shade, reflector, or the like, and is then directed outwardly to form a shoulder or projection 15, to lock under the bead of the shade or reflector, the lower end of the finger being flared outwardly, as shown at 10 16. Mounted on the spring-fingers and supported thereby is a cup or bell-shaped operating or retaining member 17, which extends longitudinally of the fixture and 15 encloses or surrounds the spring holding fingers heretofore described. This operating or retaining member 17 is freely reciprocal or movable lengthwise of the fingers 11, and the fixture, and is flared in a direction from the fixed ends of the fingers toward the free ends of the latter, so as to have an internal cone-face 18, which, when the member is moved toward the free ends of said fingers, engages the latter to hold 20 them in position to hold the bead of the shade, reflector, or the like. It will be understood that the cone-face may take a position so as to compress the fingers about the bead of the shade, reflector or the like, or 25 the cone-face can take a position adjacent the fingers to prevent them being moved outwardly sufficient to release the said bead. In order to normally maintain the member 17 in position to cause the fingers 11 to retain the shade or reflector, I provide a coiled 30 spring 19 surrounding the coupling-piece 4 and exerting its force expansively against a seat or flange 20, rigid with the inner face of said member 17, and against an abutment 35 plate 21. The abutment plate 21 is arranged concentric with the coupling-piece 4, and is preferably held in place by being clamped between said coupling-piece and the nipple 2, and is of such diameter as to 40 substantially close the upper end of the operating or retaining member 17. This plate 21 is formed with a circumferential flange 45 22 closely approaching the upper rim or edge of the member 17 and lapping the same so as to conceal the inclosed parts. This flange with its plate also forms a seat 50 for the upper end of the spring 19.

In an embodiment of my invention, as above described, the parts being constructed 55 and arranged as set forth, the operation is as follows: When a shade, reflector or the like is to be secured in place, the operating or retaining member 17 is moved lengthwise of the fingers against the force of the spring 19, so as to carry the cone-face 18 out of holding relation to the spring-fingers 11 to 60 permit the latter to be moved radially of the fixture. The position taken by this movement of the operating member 17 is shown 65 in Fig. 2. The seated or flanged end of the

shade, reflector or the like, is then pushed within the space at the free ends of the spring-fingers 11, and engaging the outwardly flared ends 16 thereof expands the fingers, the said flange or bead passing the 70 curved portion 15 into the recesses 14, whereupon the resiliency of the fingers throws them inward into locking or holding engagement with the bead or flange. The operating member 17 is then released, and the 75 spring 19 exerts its force to move the said member longitudinally of the fingers 11 and the fixture, to bring the cone-face 18 into holding relation to said fingers. As above stated, the cone-face 18 may so engage 80 the fingers as to compress them about the shade or reflector, or it may take a position relative thereto to prevent sufficient radial movement thereof to release the bead upon outward movement of the shade or 85 reflector.

In Fig. 3 I have shown the main support as consisting of a bracket arm 23 having a head 24, the latter having an integral nipple 25 having a threaded reduced end 26, 90 to receive the nipple of the socket 7. In this form the spring 19 is somewhat reduced in size over that shown in Figs. 1 and 2, and, instead of being seated on an abutment plate, is seated in an annular recess 95 27, formed by the nipple 25, and an annular flange 28 integral with the head 24, and spaced from the said nipple 25. In other respects, both as to construction and operation, this form is the same as that shown in 100 Figs. 1 and 2, and need not be further described at this point.

In Fig. 4 I have shown another embodiment of the same invention in which a bracket arm and head like that shown in 105 Fig. 3 is employed as the support, but in this form I show the operating and retaining member stamped from sheet metal, as shown at 29, instead of formed of a casting, as shown in Figs. 1, 2 and 3. I also provide a coupling-piece 31 of a slightly different construction from that shown in Figs. 1, 2 and 3, the same having an upper threaded nipple 32 threaded into the head 24 and having a lower threaded nipple 33 110 to receive the interiorly threaded nipple 34 on the lamp-socket 35. In this form of the invention, as heretofore stated, the member 29 is formed of sheet metal and is cone-shaped, but, instead of having the interior 115 flange for the spring seat, as shown in Figs. 1, 2 and 3, it is formed at its upper end with a flaring annular flange 35', forming with the upper end of the cone portion of the operating member an inwardly-projecting shoulder 36, which forms the seat for the lower end of the spring 37, the upper end of which abuts and is housed in a flanged abutment plate 38 clamped between the coupling-piece 31 and the head 24. It will be noted that 120 125

in this form the flanges 35' and the flange of the plate 38 overlap to inclose and conceal the spring. The arrangement and construction of the spring-fingers is the same as that heretofore described.

5 In Fig. 5 I have shown another form of the invention adapted for use in connection with lamp-sockets of greater length than those shown in Figs. 1, 2, 3 and 4. In this 10 form the nipple 8' of the socket 7' is screwed directly into the head 24' of the bracket arm, and clamped between the said socket and head is the center-piece 10', carrying the fingers 11'. In this form of the 15 invention the fingers, instead of flaring substantially from their point of support, extend substantially parallel to the axis of the socket and are of such length that their lower ends, having the recesses 14' will be 20 in position at the receiving or open end of the socket. The operating member consists of a cylindrical sheet-metal shell 17' having at its lower end an outwardly-flaring flange 18' having a circumferential bead 19' over 25 which is locked or crimped the flange 20' of a ring-piece 21', the latter carrying a cone part 22' projecting upwardly within the operating member. The upper small end of the said cone part 22' terminates adjacent 30 the base of the flange 18' and is formed with a radial flange 23', which forms a seat for the spring 24', which is housed between the shell 17' and the fingers 11'. The opposite end of the spring 24' from that which 35 abuts the flange 23' is seated against a flanged abutment plate 25' which overhangs the upper ends of said fingers and is clamped between the nipple 8' and the head 24', the flange of said abutment plate lapping the 40 upper end of the operating member so as to conceal and inclose the said spring. I have shown an application of the construction shown in Fig. 5 to a wall or ceiling plate in Fig. 6, in which construction I dispense with the plate 25' as shown in Fig. 5, and form the wall plate with an annular flange 39 which projects between the sleeve 17' and the fingers 11' and serves as the abutment 45 for one end of the spring 24'.

50 All of the forms shown in Figs. 1 to 6, inclusive, while not so limited, are adapted for use in connection with keyless sockets in which the current is controlled from a master switch or other switch, but, in Figs. 7 55 and 8 I show provision whereby the invention is adapted for use in connection with key-sockets. In Fig. 7 the spring fingers 11' and the plate 25' are the same as that shown in Fig. 5, but I employ an operating 60 member 40, which is substantially cylindrical in form and provided with a cone-face 41 to coöperate with said fingers in the same manner as heretofore described. This operating member is formed at its upper end with 65 a slot 42 extending longitudinally of said

member and adapted to receive the stem 43 of the key for the lamp-socket, the dimensions of the slot being such that the key may be readily rotated and the operating member may move longitudinally of the socket when 70 operated to release the spring fingers or to maintain its holding relation thereto. It will be understood that in this form two of the spring-fingers may be so spaced as to permit the stem 43 to pass between the same. 75

In Fig. 8 the spring fingers are shown at 80 44 and the construction thereof is substantially the same as that shown in Figs. 5, 6 and 7, but the abutment plate or member consists of an elongated shell 45, the lower end of which extends to a point adjacent the lower end of the lamp-socket and is provided with a cylindrical annular flange 46. Surrounding this flange is a ring member 47 carrying an upwardly and inwardly-directed annular cone-piece 48 adapted to coöperate with the spring-fingers. A spring 49 is arranged between the lower flared end of the sleeve 45 and the base of the flange 48 so as to normally urge the ring 47 to carry the 90 flange 48 into holding relation to the spring-fingers. The ring 47 may be provided with a surrounding stiffening ring 50 to prevent distortion thereof. The sleeve 45 is provided with an aperture 51 through which extends 95 the stem 43' of the lamp-socket key, which, as heretofore stated, may pass through a space between two of the spring-fingers.

The operation of all of the forms of the invention shown in Figs. 3 to 8, inclusive, 100 is substantially the same as that of the forms shown in Figs. 1 and 2, and it is not believed that it will be necessary to repeat the operation.

What I claim and desire to secure by Letters Patent of the United States is:—

1. In combination, a support adapted to support a lamp socket, means for supporting a shade, reflector or the like in operative relation thereto comprising spring clamping fingers mounted on the support, a member surrounding said fingers and having means to hold the fingers in clamping position, and a spring to move said means into holding relation with said fingers. 110

2. In combination, a support adapted to support a lamp socket, means for supporting a shade, reflector or the like in operative relation thereto comprising spring clamping fingers mounted on the support, a member surrounding said fingers and having an annular cone-surface to hold the fingers in clamping position, and a spring to move said member to place said surface in engagement with said fingers. 120

3. In combination, a support adapted to support a lamp socket, means for supporting a shade, reflector or the like in operative relation thereto comprising spring clamping fingers supported by the support, a 130

- cone member surrounding the fingers and freely reciprocable lengthwise thereof, and a spring for moving said cone into engagement with the fingers to cause them to hold 5 a shade or reflector.
4. In combination, a support adapted to support a lamp socket, means for supporting a shade, reflector or the like in operative relation thereto comprising spring 10 clamping fingers supported by the support, a member surrounding the fingers and freely reciprocable lengthwise thereof, coöperating means between the said member and the fingers whereby movement of the member 15 in one direction holds the fingers in clamping position, and in the opposite direction permits the fingers to expand, and a spring for urging the said member into holding relation with the fingers.
10. In combination, a support adapted to support a lamp socket, means for supporting a shade, reflector or the like in operative relation thereto comprising spring 20 clamping fingers mounted on the support, an annular cam surrounding said fingers to hold the fingers in clamping position, and a spring to move said cam into holding relation with the fingers.
20. 5. In combination, a support adapted to support a lamp socket, means for supporting a shade, reflector or the like in operative relation thereto comprising spring 25 clamping fingers held between the lamp socket and the coupler, and surrounding the lamp socket, an annular member surrounding the fingers, coacting means between the fingers and said member for holding the fingers in clamping position upon movement of said member in one direction, a spring exerting its force against a part fixed to the support and said member to move the member to hold the fingers.
6. In combination, a support adapted to 30 support a lamp socket, means for supporting a shade, reflector or the like in operative relation thereto comprising spring clamping fingers supported by the support, a cone member surrounding the fingers and freely 35 reciprocable lengthwise thereof, an abutment inside the cone member, and a spring housed within the cone member and exerting its force against said abutment to move the cone into holding engagement with the 40 fingers to cause them to clamp a shade, reflector or the like.
7. In combination, a support adapted to support a lamp socket, spring clamping members mounted on the support, a sleeve 45 surrounding the said fingers and movable freely lengthwise of said fingers, and adapted to hold the fingers to cause them to clamp a shade, reflector or the like, and a spring urging the sleeve into holding relation with 50 the said fingers.
8. In combination, a support adapted to support a lamp socket, spring clamping members mounted on the support, a sleeve surrounding the said fingers and movable 55 freely lengthwise of said fingers, and having a cone cam adapted to hold the fingers to cause them to clamp a shade, reflector or
- the like, and a spring urging the sleeve to cause the cam to hold the said fingers.
9. In combination, a support, a lamp 60 socket secured to the support, means for supporting a shade, reflector or the like in operative relation thereto comprising a plurality of spring-fingers secured at their upper end portion between the socket and the 65 support and flaring from their point of support, and having their lower ends provided with engaging means and located about the socket, a sleeve surrounding the fingers and supported thereby, and a spring for urging 70 the sleeve toward the lower ends of the fingers into holding engagement therewith.
10. In combination, a support, a coupler, a lamp socket connected to the coupler, means for supporting a shade, reflector or 75 the like in operative relation thereto, comprising spring clamping fingers held between the lamp socket and the coupler and surrounding the lamp socket, an annular member surrounding the fingers, coacting 80 means between the fingers and said member for holding the fingers in clamping position upon movement of said member in one direction, a spring exerting its force against a part fixed to the support and said member to 85 move the member to hold the fingers.
11. In combination, a support adapted to support a lamp socket, spring clamping fingers fixed on the support, a member surrounding the fingers and freely movable 90 lengthwise thereof to maintain them in position to clamp a shade, reflector or the like, a spring for moving said member 95 lengthwise of the fingers, and means on the member and support forming a housing concealing said spring.
12. In combination, a support adapted to support a lamp socket, spring clamping fingers fixed on the support, a member surrounding the fingers and freely movable 100 lengthwise thereof to maintain them in position to clamp a shade, reflector or the like, a spring for moving said member 105 lengthwise of the fingers, and overlapping flange members on the said member and support forming a housing concealing said spring.

In testimony whereof I have hereunto signed my name in the presence of two subscribing witnesses.

MERTON P. STEVENS.
